STEAM ENGINE

Walter Skwierawski, Milwaukee, Wis., assignor of
one-half to Isidore Z. Davidoff, Milwaukee,
Wis.

Application July 19, 1934, Serial No. 735,981

1 Claim. (Cl. 121—127)

This invention appertains to engines, and more particularly to steam engines of the reciprocating piston type.

One of the salient objects of my invention is to provide a steam engine of a simple, light and compact structure, whereby the same will be particularly susceptible for use in connection with airplanes, automobiles, and other motor vehicles.

10 Steam engines, due to the flexibility thereof and small cost of operation, are very desirable for airplanes and automobiles. Another advantage of the steam engine over an internal combustion engine for motor vehicle work is that 15 the entire cooling system, the ignition system, carburetor, muffler, etc., of the internal combustion engine can be eliminated, and the life of the engine and vehicle itself is extended as the shock of the explosions and the consequent vibrations of the gas engine are dispensed with.

One of the greatest disadvantages of the steam engine for automobiles and airplanes is the valve gear. For automobile and airplane work, it is necessary that the inlet and exhaust valves be 25 quickly opened and closed and operated in positive timed relation.

Through years of experimenting I have found that a two-cycle steam engine having positively controlled poppet valves gives the greatest efficiency, and therefore a further prime object 30 of my invention is the provision of a two-cycle steam engine having novel valves and operating means for the purpose outlined above.

A still further object of my invention is the provision of a two-cycle steam engine having poppet valves for the inlet and exhaust arranged in the cylinder head normally held on their seats by spring pressure, with means actuated from a single rock shaft for operating the valves.

40 A still further object of my invention is the provision of a rock shaft extending substantially diametrically across each cylinder, having operating fingers rigidly secured thereto and disposed in predetermined relation for engaging the stems 45 of the valves, whereby upon actuation of the rock shaft the valves will be positively operated in correct timed relation.

With these and other objects in view, the invention consists in the novel construction, arrangement and formation of parts, as will be hereinafter more specifically described, claimed and illustrated in the accompanying drawing, in which drawing:—

55 Figure 1 is a vertical transverse section through

a steam engine constructed in accordance with my invention.

Figure 2 is a fragmentary side elevation of one cylinder of my engine.

Figure 3 is a top plan view of one cylinder 5 of the engine.

Referring to the drawing in detail, wherein similar reference characters designate corresponding parts throughout the several views, the letter A generally indicates my novel engine, 10 which comprises a crank-case 5 to which are bolted, as at 6, the upright cylinders 7.

If preferred, the crank-case 5 can be constructed from upper and lower sections 8 and 9, suitably secured together, as at 10. The crank-case may carry a base 11 to permit the same to be bolted to the desired supporting structure.

Rotatably mounted in the crank-case is the longitudinally extending crank-shaft 12, and any desired bearings can be provided for the same. 20 This crank-shaft is provided with crank-arms 13, which correspond in number to the number of cylinders of the engine.

Mounted upon the crank-arm 13 is the connecting rod 14, which is in turn connected to the wrist pin 15 of the piston 16 reciprocally mounted in the cylinder 7. The piston 16 is provided with any desired type of piston rings 17.

The outer end of the cylinder 7 can be provided with an integral cylinder head 18, the opposite sides of which are provided respectively with inlet and exhaust ports 19 and 20. A manifold 22 communicates with the exhaust port. The cylinder head 18 is provided with oppositely directed inlet and exhaust valve seats 23 and 24. Poppet valves 25 and 26 are provided for the valve seats 23 and 24. The head is provided with chambers 27 and 28 which communicate respectively with the port 19 and the valve opening 23, and the port 20 and the valve opening 24. Closing the upper ends of the chambers 27 and 28 are valve guides 29 and 30. The valve stems 31 and 32 of the valves 25 and 26 extend through the guides, and suitable packing can 45 be placed around the valve stems.

By referring to Figure 1, it can be seen that the inlet valve 25 opens outwardly, while the exhaust valve 26 opens inwardly. An expansion spring 33 is placed around the valve stem 31 and 50 its opposite end bears respectively against the valve 25 and the valve guide 29 and functions to normally hold the outwardly opening valve on its seat. This stem 31 is provided with a single head, or collar, 34 on its outer end.

The stem 32 of the exhaust valve 26 is provided with a pair of spaced heads, or collars, 35 on its outer end. An expansion spring 36 is coiled about the stem 32 and bears against the 5 valve guide and the innermost head 35 for normally holding the inwardly opening exhaust valve on its seat.

One of the salient features of the invention is the arrangement of the valves and the operating 10 means 37 therefor. This operating means 37 includes a cam shaft 38 rotatably mounted in the crank-case 5, and the shaft is driven at the desired speed from the crankshaft 12 through intermeshing gears 39 keyed, or otherwise secured, 15 to the shafts 12 and 38.

The cam shaft 38 is provided with a cam 40 for each cylinder of the engine, and a push rod 41 normally bears against the cam under influence of the coil spring 42. The push rod 41 20 can be adjustable as to length, and the same slidably extends through a guide 43 secured to the crank-case.

Extending across the cylinder head 18 is a single rock shaft 44. This shaft is supported by 25 bearings 45 which can be secured to the cylinder head. One end of the rock shaft 45 is provided with a crank-arm 46, the outer end of which is connected by means of a pivot pin 47 with the push rod 41.

30 Rigidly secured to the rock shaft 44 are valve operating fingers 48 and 49. These fingers can be bifurcated, as shown, for receiving the valve stems 31 and 32. The bifurcated finger 48 extends under the head, or collar, 34, while the 35 finger 49 extends between the heads, or collars, 35 of the valve stem 32. These fingers are arranged at different angles relative to one another, so that when the fingers move up, one valve will be opened and the other valve will be 40 closed, and when the fingers move down the first valve will be closed and the other valve opened.

As stated, a plurality of cylinders is employed, and the crank-arms on the crank-shaft are arranged at different angles to eliminate the forming of a dead center and to give smooth operation. 45

In operation, steam is supplied to the manifold 21, and when the inlet valve 25 is opened steam will flow into the cylinder and force the 50 piston down. At the end of the piston stroke the inlet valve will be closed and the exhaust valve will be opened, so that upon the upstroke of the piston the spent steam will be quickly exhausted.

Referring to the valve operating means, it can be seen that in Figure 1 the fingers 48 and 49 are in their raised position and the finger 48 has lifted the head, or collar 34. The finger 49 merely moves away from the lower collar 35 5 during its upward movement, and the outer collar merely acts as a stop therefor. Upon downward movement of the fingers the finger 49 will engage the inner collar 35 and move the valve 10 off its seat against the tension of the spring 36. The finger 48 rides away from its collar 34, and hence the spring 33 firmly holds the inlet valve 25 on its seat.

As stated above, the finger 49 engages the lower collar 35 of the exhaust valve for causing 15 the positive opening of the valve, and the upper collar 35 on this valve limits the upward movement of the finger 49 so as to insure the proper positioning of this finger at all times for engagement with the lower collar 35. 20

By this arrangement, it can be seen that the valves are positively operated in proper timed relation. Changes in details may be made without departing from the spirit or the scope of my invention, but what I claim as new is:— 25

In a two-cycle steam engine, a crank case, a cylinder connected with the crank case having a head at its outer end provided with inlet and exhaust ports, a crank shaft in the crank case, a piston reciprocatively mounted in the cylinder, 30 means operatively connecting the piston with the crank shaft, a valve cam, means for operating the cam from the crank shaft, an outwardly opening poppet valve for controlling the flow of steam into the cylinder through the inlet port, 35 and an inwardly opening poppet valve for controlling the flow of spent steam through the exhaust port, guides carried by the cylinder head for the stems of the poppet valves, a pair of spaced collars on the outer end of the stem of the inwardly opening valve, a single collar on the outer end of the stem of the outwardly opening valve, a rock shaft extending across the cylinder head having a crank arm thereon, a push rod normally engaging the cam and operatively connected to the crank arm, and a pair of bifurcated fingers arranged at different angles rigidly secured to the rock shaft engaging around the collars on the stem of the inwardly opening valve, and under the collar of the stem of the outwardly opening valve. 40 45 50

WALTER SKWIERAWSKI.
